UNITED STATES PATENT OFFICE.

FLOYD L. SPENCER, OF WINDSOR, COLORADO.

WASHING APPARATUS.

Application filed October 28, 1922. Serial No. 597,481.

To all whom it may concern:

Be it known that I, FLOYD L. SPENCER, a citizen of the United States, residing at Windsor, in the county of Weld and State 5 of Colorado, have invented new and useful Improvements in Washing Apparatus, of which the following is a specification.

In carrying out the present invention it is my purpose to provide a washing apparatus 10 which will be especially useful in the washing of show windows and the like and whereby the windows may be washed and subsequently dried.

It is also my purpose to improve and simplify the general construction of washing apparatus of the class described and to provide a window washing apparatus which will embrace the desired features of simplicity, efficiency and durability, which may be manufactured and marketed at a small cost, and which will embody comparatively few parts and this so arranged and co-related as to reduce the possibility of derangement to a minimum.

With the above recited objects in view and others of similar nature, the invention resides in the construction, combination and arrangement of parts hereinafter set forth in and falling within the scope of the appended claims.

In the drawings:—

Figure 1 is a view in side elevation showing my apparatus in use.

Figure 2 is an enlarged fragmentary side elevation of the head of the apparatus showing the brush in active position.

Figure 3 is a similar view showing the brush in inactive position and the wiper in active position.

Figure 4 is a sectional view through the head.

Figure 5 is a plan view of the head partly in section.

Figure 6 is a fragmentary front elevation of the head showing the bristle block removed.

Figure 7 is a fragmentary rear elevation of the bristle carrying block.

Referring now to the drawings in detail, 50 1 designates a metal water connecting pipe which also serves as a handle of my apparatus. At the lower end the pipe 1 is equipped with a coupling 2 by which one end of a flexible hose 3 may be connected to the pipe 1, the other end of the hose 3 being adapted for connection with a water outlet

4 as illustrated in Figure 1 of the drawings. The pipe 1 is also equipped with a hand operated valve 5 by means of which the flow of water through the pipe 1 may be controlled at the will of the operator.

The other end of the pipe 1 is externally threaded to engage in one end of a socket section 6. The other end of the socket section 6 is connected to laterally extending 65 branch pipes 7 arranged at right angles to the socket section and in axial alinement with each other. These branch pipes 7 are in open communication with the pipe 1 by way of the socket section 6 so that as the 70 water flows through the pipe 1 it may pass through the socket section 6 and also through the branch pipes 7 terminating in inwardly extending axial alining nipples 8, 8, respectively. Arranged between the nipples 8, 8 is a water distributing head 9 that lies partly within the branch pipes 7, 7. This head 9, in the present instance, is in the form of a hollow casting 10 formed at opposite ends with outwardly extending 75 nipples 11 that align with the respective nipples 8, 8 and these nipples 11 are connected with the nipples 8, 8 by unions 12 so that the head may be swung about its connection with the nipples 8 and at the same 80 time permit the casting 10 to remain in open communication with the branch pipes 7.

The outer face of the casting 10, that is the face of the casting remote from the branch pipes, is formed to provide an outwardly extending discharge trough 13 that extends longitudinally of the casting and has its outer edge provided with perforations 14 spaced apart along the length of the trough as clearly shown in Figures 4 and 5 of the drawings. Arranged in face to face contact with the trough end of the casting 10 is a block 15 formed with a longitudinal slot 16 that receives the trough 13. This block 15 carries bristles 17 and constitutes a removable brush head which may be readily detached from the casting 10 when worn. In the present instance, the block 15 is held to the casting 10 by means of screws 18 or other fastening devices that pass through 105 the block and engage in the casting 10.

Integral with the inner end of the casting 10, that is the end adjacent to the branch pipes 7, and depending from said casting is an extension 19 to which is fastened as at 20 the inner end of a suitable form of clamp 21. The outer ends of the arms of the

clamp 21 carry a rubber wiper 22 and the arms of the clamp 21 are held in clamping engagement with the wiper 22 by means of a bolt 23 which when loosened permits the 5 wiper to be adjusted or removed when worn.

In accordance with my invention the outer end of one of the branch pipes 7 has fastened thereto one end of an arm 24 and connected to the arm 24 is a segment 25 10 formed with a slot 26 in which works a pin 27 carried by the adjacent end of the extension 19. This pin 27 is equipped with a thumb screw 28 adapted to bind against the segment 25 to hold the head 9 in the desired 15 adjusted position.

When it is desired to wash the window the head 9 is swung to the position shown in Figures 2 and 4 of the drawings and the thumb nut 28 tightened upon the pin 27 to 20 lock the head in such position. The valve 5 is now open and the water flows through the pipe 1, socket section 6 and branch pipes 7 into the hollow casting 10 and through the trough 13 and apertures 14 against the window thereby permitting the window to be 25 effectively washed with the brush.

After the washing operation the flow of water is stopped by closing of the valve 5 and the head 9 swung to the position shown 30 in Figure 3 of the drawings, the head being locked in this position by the thumb screw 28 on the pin 27. The wiper will now be rubbed over the window to dry the same.

In the swinging of the head to one position 35 or the other it will be understood, of course, that the thumb nut 28 is loosened so that the pin 27 may travel freely from one end of the slot 26 to the other end and when the head is in the desired position the thumb nut 40 is then tightened.

I have entered into a detailed description 45 of the construction and relative arrangement of the parts embraced in the present and preferred embodiment of my invention and in order to impart a full, clear and exact understanding of the said embodiment. I do not desire, however, to be understood as 50 confining myself to the specific construction and relative arrangement of parts inasmuch as in the future practice of the invention various changes and modifications may be made such as fall within the scope of my invention as defined in my appended claims.

Having described my invention, what I 55 claim and desire to secure by Letters-Patent, is:—

1. In washing apparatus of the class described, the combination of a hollow casting having its front end extended outwardly to

provide a trough, and the outer wall of the 60 trough perforated, a brush head detachably connected to the outer end of said casting and formed with a slot through which said trough projects, and means for conveying water to said casting. 65

2. In a washing machine of the class described, a hollow casting having a portion of its front end extended outwardly to provide a trough, and the outer wall of the trough being perforated, a brush head detachably 70 connected to the casting and formed with a slot through which said trough projects, and tubular supporting means for said casting, said supporting means also serving as a conduit for conveying water to said casting, 75 and a pivotal connection between said casting and said water supply means.

3. In a washing apparatus of the class described, a hollow casting having a portion of its front end extended outwardly to provide a trough and the outer wall of the trough being perforated, a brush head detachably connected to the casting and formed with a slot through which said trough projects, and tubular supporting 80 means for said casting, said supporting means also serving as a conduit for conveying water to said casting, and a pivotal connection between said casting and said water supply means, and co-engaging elements 85 carried by said casting and said water supply means whereby said head may be locked in different positions.

4. In an apparatus of the class described, a water conveying pipe adapted to act as a handle, means for connecting one end of said pipe with a source of water supply, branch pipes connected to the other end of said first mentioned pipe extending laterally therefrom in opposite directions and having their outer extremities formed with in-turned nipples, a head arranged between said nipples, comprising a hollow casting, connections between the ends of said hollow casting and said nipples whereby water may be delivered to said casting, a brush carried by the outer end of said casting, said outer face of the casting being formed with apertures whereby the water may be discharged through said brush, and means for governing the flow of water through said casting, and cooperating elements carried by said head and one of said branch pipes to lock the said head in different positions. 100 105 110

In testimony whereof, I affix my signature. 115

FLOYD L. SPENCER.
